UNITED STATES PATENT OFFICE.

HARRY GREENBERG, OF BROOKLYN, NEW YORK.

DIE PRESS.

Application filed January 16, 1924. Serial No. 686,502.

My invention relates to improvements in cutting, punching, stamping, and similar machines, and more particularly has reference to and is illustrated in the accompanying drawings in its application to a machine for blanking out collar bands and similar articles from fabrics preferably laid upon a movable table or platform.

Heretofore it has been customary to employ a detached die which is shifted by hand between the strokes of the plunger of the machine for cutting out blanks such as referred to. This is a slow method, is inexact, requires constant expert attention, and is more or less dangerous to the operator, whereas according to my present method, the dies while detachable are movably attached to the plunger and automatically fed preferably transversely across the length of the goods or fabric in predetermined space, thereby cutting with exactness and nicety through the fabrics piled upon the table, avoiding waste, saving time, minimizing danger, and saving space for the number of machines required for a given output of material.

In the accompanying drawings, I have illustrated in Fig. 1 in front elevation, a suitable form of blanking or cutting machine embodying an application of my invention. Fig. 2 is a side elevation of the same. Fig. 3 is an enlarged longitudinal view partly broken away and partly in section illustrating the feed bar or rod for the carriage containing the die or cutting tool, and Fig. 4 is a view looking from right to left thereat.

5 indicates the usual frame of a cutting or blanking machine of the type referred to, and 6 is the cross head or plunger thereof. Power may be transmitted by belt or otherwise to a pulley such as 7 upon a shaft upon which is mounted a gear 8 which when shifted leftwardly engages the gear 9 upon the shaft 10 said gear 9 meshing with gear 9' upon shaft 10' which carries the eccentric 11 connected by rods 12 to the projection 13 of the head 6, thereby giving vertical reciprocation to said head, and upon said head are suitable brackets such as 14—14' which carry the bar 15 having a longitudinal recess 16 within which racks or tooth members such as 17 may be introduced against the tension of a resiliently projected head such as 18.

19 indicates a suitable carriage adapted to

slide along the bar 15 and is provided with a pawl 20 pivoted at 21 in the frame of said carriage as shown, and provided with a roller 22 in the other end of said pawl immediately beneath the bar 23, which bar 23 is in turn pivotally mounted at 24, the front being retained by the spring 25. At one end of said bar 23, a projecting member 26 is pivotally secured to the head 6 as shown and is adapted to travel vertically in the path of the projecting member 27 pivotally mounted in the frame of the machine as indicated at 28, so that as the projection 26 moves downwardly it readily passes the projection 27, but upon the return or upward movement of the projection 26, the left end of the projection 27 is engaged above the right end of the projection 26, thereby causing the frame 23 to be thereby pulled downwardly striking the roller 22 and depressing the left end of the pawl 20, releasing the same from a notch in the rack 17, and the carriage 19 being retained at one end of the strap 30 is pulled leftwardly, allowing the pawl 20 to engage the next left succeeding notch, the strap 30 being wound upon a resilient drum 31' for the purpose of drawing the carriage 19 leftwardly.

With each downward move, therefore, of the plunger 6, the carriage 19 is moved leftwardly one step a predetermined distance so as to cut through another section of the fabric 31 upon the table 32.

33 indicates the die which is slidably mounted within the frame or carriage 19 so that it can be pulled toward or pushed away from the operator to any desired extent. Likewise the table 32 can be brought forward upon the rollers 31' or pushed backward into the machine as may be found desirable for adjustment, and in this way the entire length of the layers of fabric 31 can be punched or cut in successive transverse lines until the entire fabric has been used up, the successive transverse cuttings being separated a predetermined extent according to the particular rack or notched bar 17 used and which bar is of course changed with different dies for different cuttings.

Of course it will be understood that various modifications may be made in the construction and arrangement of parts without departing from the spirit of the invention as claimed.

I claim:

1. In a machine of the class described, a

- hinged U-shaped bar resiliently retained upon the front of the plunger head of said machine, another bar beneath the same upon said head having spaced apart engaging means, a carriage and means for feeding the same along said other bar and beneath said first mentioned bar, and means in combination with said carriage adapted to be operated by said first mentioned bar for engaging and disengaging said engaging means, and in combination with said first mentioned bar, means for operating the same with each movement of said plunger head.
2. In a machine of the class described, a cutting block, a die, a die holder, means for moving the die and die holder to and from said block, two supports transversely of said machine adapted to slidably and entirely carry said die holder, one of said supports having recesses determining the movement of said holder, and means for shifting said holder step by step along said supports engaging and disengaging successively said recesses.
3. In a machine of the class described, a cutting block, a die, a die holder, means for moving the die and die holder to and from said block, two supports upon and at either side of adapted to slidably carry said die holder, one of said supports having a series of stops, and means for moving said holder

step by step successively in and out of said stops across said machine, said means for moving said holder located only at opposite sides of said machine.

35

4. In a machine of the class described, a cutting block, a die, a die holder, means for automatically depressing said holder and for moving the same laterally a predetermined distance each time the same is depressed, a bar having retaining means, means upon said holder for engaging the same, and means operatively connected with the driving mechanism of said machine for periodically and successively disconnecting said retaining and engaging means.

40

5. In a machine of the class described, a cutting block, a die, a die holder, means for automatically depressing said holder and for moving the same laterally a predetermined distance each time the same is depressed, a bar having retaining means, means upon said holder for engaging the same, and means operatively connected with the driving mechanism of said machine for periodically and successively disconnecting said retaining and engaging means, said last mentioned means comprising a substantially vertically movable transversely extending member.

50

In testimony whereof I hereunto affix my signature.

HARRY GREENBERG.
